JOHN H. DOMKEE, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

SLIDE BUCKLE

Application filed September 26, 1931. Serial No. 565,322.

This invention relates to slide buckles used for adjusting the length of looped straps, webbing and the like, without penetrating the material, and, while the invention is adapted 5 to any bent wire form of slide buckle, it is especially adapted to that class of slide buckles made of round wire bent to form a pair of loops connected at one side and free at the opposite sides and having intermediate 10 bar-structure portions integrally extending from the free sides of the loops to the connected side thereof.

The objects of the invention are to provide a reversible slide buckle having strap-gripping 15 bar-structures flattened in the plane of the buckle and also bar-structures having spaced projections extending out of the said plane; to provide a slide buckle of the pair of loops type of which the upper and lower 20 bar-structures are flattened in the plane of the loops, and the intermediate bar-structures are provided with spaced projections extending in opposite directions out of said plane; to provide means for securing together 25 the free sides of such a pair of loops; and to provide means for securing the wire ends of the intermediate bar-structure portions to the connected side of the loops. With these and other objects in view as may become apparent 30 from the within disclosures, the invention consists not only of the particular form herein pointed out and illustrated in the drawing, but readily admits of certain modifications within the scope of what hereinafter 35 may be claimed.

While the character of the invention is broad in its application to the art, reference is here made to one illustrative device embodying the invention and illustrated by the 40 accompanying drawing in which the Figure 1 is an upright elevation of the device; the Figure 2 is a cross-section on the line "2—2" of the previous figure; the Figure 3 is a cross-section on the line "3—3" of the Figure 1; the Figure 4 being an upright elevation of a modified form of the device.

The device about to be described is an improvement upon the devices described by the patents numbered 1,810,647 and 1,672,263 45 issued to your petitioner June 16, 1931, and

June 10, 1930, respectively, on slide buckles of which both of the intermediate bar-structures are provided with angular formations projecting in planes perpendicular to, and out of, the plane of the buckle. Referring more 55 particularly to the drawing, however, the slide buckle as illustrated is provided with projections formed, not by bending the wire but by pressing spaced portions of the wire to form nubs projecting therefrom and the 60 upper and lower bar-structures are flattened in the buckle plane. The device is preferably made from a single piece of round wire of which a middle portion provides the integrally connected side bar 1 of a pair of 65 loops 2 and 3 lying in a common plane and formed by bending both wire end portions in substantial parallel relation to provide the upper and lower horizontal bar-structures 4 70 and 5 of the pair of loops 2 and 3, both wire end portions again being bent, but inwardly toward one another, to provide the relatively free sides 6 and 7 of the pair of loops 2 and 3, and both wire end portions again being 75 bent inwardly and substantially parallel 80 with the upper and lower horizontal bar-structures 4 and 5 to leave the free sides 6 and 7 in substantially relative engagement and to provide the intermediate bar-structure portions 8 and 9 separating the pair of loops 85 2 and 3, the intermediate bar-structure portions 8 and 9 extending across the buckle and engaging, within the plane of the loops 2 and 3, with the connecting side bar 1. At some convenient step in the formation of 90 the slide buckle, as aforesaid, the spaced nubs 12 are pressed out of the metal of the round wire intermediate bar-structure portion 8 so that the nubs 12 project therefrom out of the said plane of the loops 2 and 3, and the 95 spaced nubs 13 are pressed out of the metal of the round wire intermediate bar-structure portion 9 so that the nubs 13 project therefrom out of the said plane in a direction opposite to that of the nubs 12, and the upper 95 and lower horizontal bar-structures 4 and 5 each having an inner edge portion 14 flattened in the plane of the loops 2 and 3. To prevent accidental or wanton separation of 100 the relatively engaging free sides 6 and 7 of

the loops 2 and 3, the engaging metal surfaces at the free sides 6 and 7 are united, as at 15, in permanent intimate unit, as by welding, brazing or soldering, so that the original 5 character of said metal surfaces cannot be restored by any force effecting the mere separation of the loops 2 and 3 at that place, and the engaging metal surfaces of the extremities 10 and 11 and the connecting side bar 1 10 are likewise united in permanent intimate union, as at 16 within the plane of the buckle to provide a rigid structure of the aforesaid form that is reversible in the sense that the elevation opposite to that illustrated by the 15 Figure 1 is substantially identical to the elevation as thus illustrated. While the engaging metal surfaces of the loops 2 and 3 at their free sides 6 and 7, and the engaging metal surfaces of the extremities 10 and 11 20 of the intermediate bar-structure portions 8 and 9 and the connecting side bar 1 are illustrated and described as preferably being united in permanent intimate union, these engaging parts of the device each may be 25 relatively secured, if desired, in any less permanent and intimate manner.

In use, a strap 17 may be threaded into the slide buckle, as illustrated by the Figure 2, so that the flattened inner edges of the upper and lower bar-structures 4 and 5 and the spaced nubs 12 and 13 extend in different 30 directions into the path of the threaded strap 17 to grip the strap from different angles to prevent the slide buckle sliding 35 upon a taut strap threaded therethrough.

The modified form of the device, illustrated by the Figure 4, materially differs from the preferred structure only in that the nubs 12' and 13' are provided by an intermediate 40 bar-structure portion 8' and the upper and lower horizontal bar-structure 4' and 5' are flattened substantially throughout, not only their entire length but their entire width as well, but both modified and preferred forms 45 of the device are similar in that they each provide gripping edges and nubs extending in different directions into the path of a strap threaded into the slide buckle, the modified form having engaging metal surfaces, 50 as at 15' and 16' united in permanent intimate union as in the preferred form.

I claim:—

1. A slide buckle structure comprising a 55 piece of wire of uniform diameter throughout its length and bent to form a substantially rectangular frame having side, upper, lower and intermediate bar-structures, the upper and lower bar-structures being flattened in the plane of the frame and the intermediate bar-structure being provided with spaced nubs, each nub being pressed out from 60 said uniform diameter to extend beyond the bar-structure of which a full diameter is maintained between, and at the rear of said 65 nubs, said nubs extending out of said plane

in opposite directions and cooperating with the inner edges of the flattened bar-structures to grip a strap threaded into the slide buckle.

2. A slide buckle comprising a piece of wire of uniform diameter throughout its length 70 and bent to form a pair of loops in a common plane, the loops being integrally connected at one side and free, but engaging one with the other, at the opposite sides, intermediate bar-structure portions integrally extending 75 from the free sides to engage their extremities with the connected side, the upper and lower bar-structures being flattened in the plane of the frame and the intermediate bar-structure portions being provided with spaced 80 nubs, each nub being pressed out of said uniform diameter to extend beyond the portions of the intermediate bar-structure of which portions a full diameter is maintained between, and at the rear of said nubs, said nubs 85 extending out of said plane in opposite directions and cooperating with the inner edges of the flattened bar-structures to grip a strap threaded into the slide buckle, means uniting in permanent intimate union the engaging 90 metal surfaces of the free sides of the loops, and means likewise uniting the engaging metal surfaces of the extremities with the metal surface of the integrally connected side 95 of the loops.
